UNITED STATES PATENT OFFICE

2,000,741

FLUID JET PUMP

Bruce O. Buckland, Schenectady, N. Y., assignor
to General Electric Company, a corporation of
New York

Application October 26, 1933, Serial No. 695,249

4 Claims. (Cl. 103—267)

The present invention relates to fluid jet pumps or injectors for conveying a fluid by means of a fast-moving stream of the same or another fluid and converting the velocity energy of the mixture into pressure energy in a diffuser.

In pumps or injectors of this type in which the jet or jets of fast-moving or impelling fluid are discharged centrally in the direction of the axis of the diffuser, instabilities occur due to the formation of a boundary layer of slowly moving fluid within the diffuser.

One object of the present invention is to provide an improved construction for pumps of the type above referred to in which the boundary layer is readily removed or substantially minimized in thickness.

For a consideration of what I believe to be novel and my invention, attention is directed to the following description and the claims appended thereto in connection with the accompanying drawing.

In the single figure of the drawing I have shown a sectional view of a jet pump embodying my invention. The pump comprises a casing defining a suction chamber 10 having an inlet 11 for receiving fluid to be conveyed and a diffuser or discharge conduit 12 having a diverging or diffuser portion in which the diffusion takes place. A nozzle 13 fastened to the casing by means of bolts 14 opens into the chamber in the direction of the axis of the diffuser. The arrangement so far described is generally known in the art. During operation a fluid under pressure is discharged through the nozzle 13 into the suction chamber 10, where the jet or jets from the nozzle 13 entrain and increase the velocity of the fluid entering the inlet 11. The resulting mixture suffers a reduction in velocity and an increase in pressure in its passage through the diffuser 12.

A typical application of pumps of this kind is their use for conveying feed-water to a boiler by means of elastic fluid received from the boiler and discharged through the nozzle 13 into the suction chamber. In this particular case steam discharged from the nozzle 13 mixes with the water supplied through the inlet 11 whereby the steam condenses and creates a vacuum. As pointed out above, the mixture of fluid in the diffuser forms a boundary layer which moves very slowly or not at all and thereby renders the pump unstable and reduces its efficiency. In accordance with my invention this boundary layer is effectively removed by the provision of

recesses or slots in the wall surface of the diffuser or discharge conduit and connecting these recesses to a point or points of lower pressure.

In the present instance I have shown two annular slots or recesses 15 axially spaced apart and provided in the wall of the diffuser. The diffuser wall defining these slots has bulges 16. The slots are connected to the suction chamber 10 by means of conduits 17. During operation the slowly moving boundary layer, being under a pressure higher than the pressure existing in the suction chamber 10, is discharged through the conduits 17 into the suction chamber. It is noted that the slots or recesses 15 are provided in the diverging or diffuser portion of the conduit 12 where the diffusion takes place. The withdrawal of the boundary layer in the diffuser renders the operation of the jet pump more stable in that it reduces the tendency of backflow of the boundary layer at certain points of the diffuser. Backflow of the boundary layer leads to whirling which reduces the efficiency of a jet pump.

In addition to the means just described for removing the boundary layer I may provide an auxiliary nozzle arrangement for injecting impelling fluid in tangential direction along the walls of the diffuser. To this end flanged portions 18 uniting the suction chamber with the diffuser are recessed to define an annular channel 19 connected to a conduit 20 for receiving impelling fluid and discharging through one or a plurality of nozzles 22 into the diffuser. The impelling fluid discharged from the annular channel 19 accelerates the slowly moving boundary layer and thus aids in removing the boundary layer. The arrangement of the auxiliary slots forms a part of and is more fully disclosed in the application of Hans Kraft, Serial No. 695,299, filed on the same date with the present application.

It will be readily understood that my invention which comprises the provision of a plurality of grooves or slots in the diffuser wall and means for discharging the boundary layer through the slot or slots to a point or points of lower pressure may be used singly or together with the auxiliary nozzle arrangement.

With my invention I have accomplished an improved construction of fluid jet pumps or injectors which are stable during operation and in addition have a higher efficiency than ordinary jet pumps.

Having described the method of operation of my invention, together with the apparatus

which I now consider to represent the best embodiment thereof, I desire to have it understood that the apparatus shown is only illustrative and that the invention may be carried out by other means.

5 What I claim as new and desire to secure by Letters Patent of the United States is:

1. In a jet pump, a casing defining a suction chamber with an inlet for fluid to be conveyed and a discharge conduit having a flaring diffuser portion, a nozzle for discharging a jet of impelling fluid into the chamber in the direction of the axis of the conduit, and conduit means connected to the flaring portion for removing a slowly moving boundary layer of fluid in said flaring portion to maintain stability during operation.
2. In a jet pump, a casing defining a suction chamber with an inlet for fluid to be conveyed and a discharge conduit having a flaring diffuser portion, a nozzle for discharging a jet of impelling fluid into the chamber in the direction of the axis of the conduit, and means for removing a slowly moving boundary layer of fluid in the conduit comprising at least one circumferentially extending slot in the flaring portion of the discharge conduit connected to a point of lower pressure.

3. In a jet pump, a casing defining a suction chamber with an inlet for fluid to be conveyed and a discharge conduit having a flaring diffuser portion, a nozzle for discharging a jet of impelling fluid into the chamber in the direction of the axis of the conduit, and means for removing a slowly moving boundary layer of fluid in the flaring portion of the conduit comprising a plurality of axially spaced apart circumferentially extending recesses in the flaring portion of 10 the discharge conduit and conduits connecting the recesses to points of lower pressure.

4. In a jet pump, a casing defining a suction chamber with an inlet for fluid to be conveyed and a discharge conduit having a flaring diffuser 15 portion, a nozzle for discharging a jet of impelling fluid into the chamber in the direction of the axis of the conduit, and means for removing a boundary layer of fluid in the flaring portion of the conduit comprising a plurality of concentric axially spaced apart annular slots in the flaring portion of the discharge conduit and conduits connecting said slots to the suction chamber.
